CLAIM

We claim the ornamental design for a beverage dispenser display screen with animated graphical user interface, as shown and described.

DESCRIPTION

FIG. 1 is a front view of a first image of a beverage dispenser display screen with animated graphical user interface, showing our new design;

FIG. 2 is front view of a second image thereof; and,

FIG. 3 is front view of a third image thereof.

The appearance of the image sequentially transitions between the images shown in FIGS. 1 through 3. The process or period in which one image transitions to another forms no part of the claimed design.

The outermost broken line illustrates a display screen and forms no part of the claimed design. The remaining broken
